SLIDING DRAWER CONSTRUCTION

Charles M. Abrahamson and Karl P. Grube,
Aurora, Ill., assignors to All-Steel Equipment
Inc., a corporation of Illinois

Application December 6, 1949, Serial No. 131,400

9 Claims. (Cl. 312—346)

1

This invention relates to drawer slides, particularly those used in desks and cabinets.

The main objects of this invention are to provide improved means for slidably supporting a drawer on housing guides so as to render the sliding movement of the drawer quiet and facile; to provide an improved construction and arrangement of special composition buttons on the drawer slides and the housing guides to carry the weight of the drawer in its sliding movements; to provide an improved form and manner of stamping the drawer slides which minimizes the waste of material; and to provide a drawer mounting and locking means of this kind which is economical to manufacture and highly efficient in use.

In the particular embodiment shown in the accompanying drawings:

Fig. 1 is a fragmentary, vertical, sectional elevation of a desk pedestal showing the drawer slide and guide channel mountings and the locking means for a tier of drawers;

Fig. 2 is an enlarged, fragmentary, cross-sectional detail of the locking means, taken on the line 2—2 of Fig. 1;

Figs. 3, 4 and 5 are perspective views of the several forms of composition buttons which slidably support the drawers for movement on the desk pedestal;

Fig. 6 is a plan view showing how the right and left drawer slides are cut from a single piece of sheet material with a minimum amount of waste;

Fig. 7 is an exploded perspective of a drawer slide and pedestal guide channel and a part of the locking means for one drawer constructed in accordance with this invention;

Fig. 8 is an enlarged, fragmentary plan view showing the locking detent whereby a drawer is secured in its closed position by the locking means; and

Fig. 9 is a sectional view taken on the line 9—9 of Fig. 1.

The improved sliding drawer construction embodying this invention is shown applied to a metal desk having pedestals 10, one of which is shown, and is adapted to slidably mount a tier of drawers 11 through the coaction of guide channels 12 and drawer slides 13, the channels and slides being equipped with specially formed drawer-support buttons 14, 15 and 16, and which drawers may be secured in their closed positions by a locking mechanism, generally designated 17.

The pedestal 10 may be of any suitable construction. It is herein shown as formed of sheet metal and comprises pairs of front and rear uprights 18 and 19 between which extend sheet

2

metal panels 20 and 21 and upon which rests a desk top 22.

The drawer 11, wherewith this invention is associated, is also preferably sheet metal. It is formed in the usual manner with a depth and width dependent upon the size of the pedestal 10 and the number of drawers arranged therein. Along its upper edges, the drawer is formed with reinforcing rims 23 (see Fig. 2).

10 The guide channels 12, as herein shown, are right and left sheet metal stampings. A pair for each drawer is secured in opposed relationship on the pedestal uprights 18 and 19. At the forward ends of these guides 12 the transverse flanges 24 and 25 terminate short of the end of the channel base 26, as most clearly shown in Fig. 7.

Various lugs are struck out from the base 26 of each of the guides 12. The pairs of lugs 27 at the forward end and a lug 28 at the rear end 20 provide for attachment of each guide channel to the pedestal legs. The pairs of lugs 29 provide support for a locking bar 30, forming a part of the locking mechanism 17, as will be described more fully hereinafter. The lug 31 provides a stop for 25 limiting the outward movement of the drawer 11.

15 The drawer slides 13 are likewise right and left sheet metal stampings, as shown in Fig. 6. As indicated, a pair of slides is cut from a single piece of material, the part between the slide stampings 13 being usable for other purposes such as, for example, forming the locking bar 30. Each of the slides 13 is formed with spaced extensions or projections along one side face which are subsequently formed to provide a socket 32 at the forward end for retaining a cylindrical cushioning element 32' abutting the stop 31 as the drawer 11 reaches its fully closed position, a stop 33 for co-acting with the locking mechanism 17, an upper flange 34 at the rear end, and a shoulder 35 co-acting with the lug 31 on the guide channels 12 35 for limiting the outward movement of the drawer, but which permits the drawer to be removed when properly tilted upwardly. The lower perimetrical portion of each drawer slide is bent to form a base flange 36 transverse to the main part of the slide 13 and an auxiliary flange or ledge 37 disposed parallel to the main part of the slide 13.

40 Because the contact of the drawer slides 13 and guide channels 12 is confined to the buttons 14, 15 and 16 only a short upper flange 34 is required. The elimination of the perimetrical portion forwardly of the flange 34, except for the extensions which form the stop 33 and the shoulder 35, saves material and contributes to lightening overall weight.

The buttons 14, 15 and 16 provide the only points of contact between the guide channels 12 and the drawer slides 13. Their purpose is to make the sliding of the drawers much easier and more quiet than is afforded by the conventional direct metal-to-metal sliding contact. To that end, these buttons are formed of a material that has an inherent quality of lubricity so that they provide a smooth, slippery contact with the metal parts which they contact. The synthetic substance commonly known as "nylon" has been found to possess this quality of lubricity to a very acceptable degree, and in this particular embodiment, the buttons 14, 15 and 16 are formed of that material. The result is a drawer which shifts with the ease and quietness comparable to that obtained by the use of roller bearings. However, the cost of construction is materially less than that of a roller bearing construction. Each button is formed with a stem 38, which is insertable with a tight fit in a suitable opening in either the drawer slide 13 or guide channel 12 for anchoring the buttons to the respective parts.

A button 14 is secured to the upper face of the flange 34 of each of the drawer slides 13 at the rear ends thereof with the flange 39 on the button 14 extending over the edge of the flange 34 and contacting the base 26 of the opposed guide channel 12. A button 15 is arranged on the upper face of the flange 25 of each of the guide channels 12 adjacent the forward ends, with the button flange 40 abutting the base 26 of the respective guide channel 12 and providing contact with the face 41 of the auxiliary flange 37 of the opposed drawer slide 13. The flange 37 makes it possible for a smooth face of the drawer channel to ride against the lip or flange 40 of the button 15, with the result that friction and noise are held to a minimum. When desired, a button 16 also may be secured to the underface of the flange 36 on each of the drawer slides 13, slightly inward from the rear end of the slide, so as to bear on the inner face of the flange 25 of the opposed guide channel 12.

The locking mechanism 17 comprises the locking bar 30, whereto is attached a detent 42 for each drawer 11 in the pedestal 10, and which bar is operatively connected to a lock 43 and normally urged by a spring 44 into its locking position.

The locking bar 30 is slidably supported between the flanged lugs 29 on the several channel guides 12 on one side of the pedestal 10. The upper end of the bar is bent at right angles to provide an arm 45 which is connected to a locking bolt 46 for the lock 43. Recesses 30' (see Fig. 1) are formed in the edges to permit the insertion of the bar 30 into the flanged lugs 29.

The detents 42 are preferably spring metal, each being anchored at one end to the locking bar 30 by one or more rivets 47. From the point of its fastening, each detent 42 is angularly disposed to the line of travel of a drawer 11 (see Fig. 8) so that the end of the detent is normally disposed in the path of travel of the stop 33 on the respective drawer. Hence, when the bar 30 is depressed, each detent 42 will engage its respective stop 33 and secure the corresponding drawer against being opened.

Being so formed and positioned, these detents 42 permit the operation of the locking bar 30 to 70 secure any drawer in its closed position, notwithstanding the fact that one or more of the other drawers may be in a partially open position at the time the lock 43 is operated. If, when the bar 30 is thus shifted, a drawer is partially open, a sub-

sequent closing of the drawer will cause the inclined surface 49 on the stop 33 to deflect the detent 42 to permit the closing of the drawer, whereupon the detent 42 will spring into position shown in Fig. 8, to secure such drawer, along with the others, in its closed position.

The lock 43 may be of any suitable form. Preferably, it is mounted on the inner pedestal wall near the front so as to be conveniently accessible to one sitting at the desk.

The spring 44 is connected at one end to the arm 45 of the locking bar 30 and at the other end to a bracket 48 secured to the pedestal side 20 adjacent the lock 43.

Obviously, the invention may be variously embodied within the scope of the appended claims.

We claim:

1. A sliding drawer construction comprising, a housing having a drawer compartment, a drawer shiftable in said compartment, horizontally-disposed guide channels fixed on the sides of said housing, a slide longitudinally disposed along each side of said drawer and having a horizontal flange extending into the respective guide channels, buttons of lubric material secured at the inner ends of said slides to bear upon the underfaces of the upper flanges of each of said guide channels, and other buttons of lubric material secured to the upper faces of the lower flanges of said guide channels adjacent the forward ends thereof, said buttons providing the sliding contact between said guide channels and slides for the shifting of said drawer, said buttons each having a vertical flange portion, a horizontal body portion and a vertical stud portion, said first-mentioned buttons each having their stud portion passing through an opening in said horizontal flange of the slide, with the body portion resting on said horizontal flange and with the vertical flange portion overhanging the edge thereof, whereby said overhanging vertical flange portion of the button prevents the slide from making contact with the adjacent portion of the guide channel and also prevents rotation of the button about the stud portion within said opening.

2. A sliding drawer construction comprising, a housing having a drawer compartment, a drawer shiftable in said compartment, horizontally-disposed guide channels fixed on the sides of said housing, a slide on each side of said drawer formed with a flange along its lower edge for reception in the opposed guide channel, said slide flange being turned upward along its perimeter to provide an auxiliary flange disposed parallel to the body of said slide and opposed to the base part of the web of said opposed guide channel, each of said slides also being formed with a transverse flange along the rear end thereof for reception in the opposed guide channel, buttons of lubric material secured to the upper and underfaces of said slide flanges adjacent the rear ends thereof and adapted to bear respectively against the inner faces of the upper and lower flanges of said guide channels, and other buttons of lubric material secured to the inner faces of the lower flanges of said guide channels to bear against the undersides of the lower slide flanges, said buttons providing the only contact between said drawer slides and said channel guides for the shifting of said drawer, said other buttons each having a vertical flange portion, a horizontal body portion, and a vertical stud portion, the stud portion of said other buttons passing through an opening in the lower flange of the guide channel with the horizontal body portion of the button

resting on the top face of said lower flange, and with the vertical flange portion of the button extending upwardly and interposed between the web of the adjacent channel and said upwardly-turned margin of the slide flange, whereby said vertical flange portion of the button prevents physical contact between the slide and the adjacent channel at the forward end of the channel and also prevents rotation of the button about said stud portion.

3. A sliding drawer construction comprising, a housing having a drawer compartment, a drawer shiftable in said compartment, horizontally-disposed guide channels fixed on the sides of said housing, a slide on each side of said drawer formed with a flange along its lower edge for reception in the opposed guide channel, said slide flange being turned upward along its perimeter to provide an auxiliary flange disposed parallel to the body of said slide and opposed to the base part of said opposed guide channel, each of said slides also being formed with a transverse flange along the rear end thereof for reception in the opposed guide channel, buttons of lubric material secured to the upper and underfaces of said slide flanges adjacent the rear ends thereof and adapted to bear respectively against the inner faces of the upper and lower flanges of said guide channels, and other buttons of lubric material secured to the inner faces of the lower flanges of said guide channels to bear against the undersides of the lower slide flanges, the buttons on the rear upper flanges of said slides having a part thereof extending downwardly over the edge of said slide flanges and adapted to contact the opposed faces of the base of said guide channels and the buttons on said guide channel having a part thereof extending upwardly and disposed against the base of the respective guide channels and adapted to contact the opposed face of said auxiliary flange, said buttons providing the only contact between said drawer slides and said channel guides for the shifting of said drawer.

4. A sliding drawer construction comprising, a housing having a drawer compartment, a drawer shiftable in said compartment, horizontally-disposed guide channels fixed on the sides of said housing, a slide on each side of said drawers formed with a flange along its lower edge for reception in the opposed guide channel, said slide flange being turned upward along its perimeter to provide an auxiliary flange disposed parallel to the body of said slide and opposed to the base part of said opposed guide channel, each of said slides also being formed with a transverse flange along the rear end thereof for reception in the opposed guide channel, nylon buttons secured to the upper and underfaces of said slide flanges adjacent the rear ends thereof and adapted to bear respectively against the inner faces of the upper and lower flanges of said guide channels, and nylon buttons secured to the inner faces of the lower flanges of said guide channels to bear against the undersides of the lower slide flanges, the buttons on the rear upper flanges of said

slides having a part thereof extending downwardly over the edge of said slide flanges and adapted to contact the opposed faces of the base of said guide channels and the buttons on said guide channel having a part thereof extending upwardly and disposed against the base of the respective guide channels and adapted to contact the opposed face of said auxiliary flange, said buttons providing the only contact between said drawer slides and said channel guides for the shifting of said drawer.

5. For use as an anti-friction device in sliding drawers, a one-piece button of lubric material having a flat body portion, a stud portion projecting laterally therefrom, and a laterally extending flange along one margin of said body portion.

6. The button as set forth in claim 5 in which the stud portion projects laterally from said flat body portion in the same direction as said laterally extending flange.

7. The button as set forth in claim 5 in which the stud portion projects laterally from said flat body portion in the opposite direction from said laterally extending flange.

8. For use as an anti-friction device in sliding drawer constructions of the type having a member provided with a horizontal wall, a button of lubric material having a body portion adapted to seat upon said horizontal wall, and having a stud portion normal thereto adapted to pass through a mating opening in said wall, said button also including a marginal projection extending laterally from said body portion in a direction parallel to said stud portion.

9. The method of providing smooth sliding engagement between relatively sliding members of a drawer suspension in which one of said members includes a horizontal wall, which consists in mounting on said wall an anti-friction button of lubric material having a body portion adapted to seat upon said wall, and having a stud portion normal thereto adapted to pass through a mating opening in said wall, said button also including a marginal projection extending laterally from said body portion in a direction parallel to said stud portion.

CHARLES M. ABRAHAMSON.
